[57] CLAIM

The ornamental design for a fast pass card reader unit, substantially as shown and described.

DESCRIPTION

FIG. 1 is a perspective view of a fast pass card reader unit, showing my new design;

FIG. 2 is a bottom plan view thereof;

FIG. 3 is a side elevational view thereof, the opposite side being a mirror image;

FIG. 4 is an end elevational view thereof, the opposite end being a mirror image.

FIG. 1

FIG. 2

FIG. 3

FIG. 4
